His Attorney.

UNITED STATES PATENT OFFICE

2,286,023

PNEUMATIC OPERATING MECHANISM FOR
CIRCUIT BREAKERS

Harold E. Strang, Ardmore, Pa., assignor to General Electric Company, a corporation of New York

Application July 11, 1940, Serial No. 344,965

6 Claims. (CL 200—82)

My invention relates to pneumatic operating mechanisms having particular application to circuit breakers, and has particular reference to mechanisms of the trip-free type where the means to be actuated, such as a circuit breaker, can be released with respect to the actuating or closing means during the course of the closing stroke and prior to completion thereof.

Heretofore, circuit breaker operating mechanisms of the trip-free type have generally included a collapsible linkage arrangement or the like involving a more or less complicated design of toggles, levers and latches. Since the trip-free type mechanism is required to be very rapid in action due to the fact that immediate trip-free operation of the circuit breaker is essential when the circuit breaker is closed on a fault current, mechanical arrangements have been preferred to known pneumatic types in view of the high speeds of operation that have been obtained with certain mechanical mechanisms.

A principal object of the present invention is the provision of an improved and simplified trip-free mechanism of the pneumatic or fluid operating type that is efficient, positive and rapid in operation, rugged and compact in design and composed of comparatively few essential operating elements.

My invention will be more fully set forth in the following description referring to the accompanying drawing, and the features of novelty which characterize my invention will be pointed out with particularity in the claims annexed to and forming a part of this specification.

Referring to the drawing, the single figure thereof is a diagrammatic view, partly in section, of a pneumatic operating mechanism for an electric circuit breaker embodying the present invention.

The pneumatic mechanism illustrated by way of example comprises essentially a source of operating fluid pressure indicated at 1, a fluid motor or actuating means 2 and the means to be actuated comprising in the present instance the operating means 3 of an electric circuit breaker (not shown). The source of fluid pressure is preferably compressed air, although it should be understood that any suitable fluid medium, preferably elastic, under pressure can be employed. The fluid motor 2 comprises an operating piston 4 disposed for reciprocal movement in a cylinder 5 that is arranged to be in communication with the source 1 through a control valve 6. The piston 4 is provided with a plunger 7 operatively related to a lever 8 that is pivotally

mounted at 9 and connected at 10 to the circuit breaker rod 11. The piston plunger is arranged to engage a roller 12 carried by the lever 8 and to rotate the lever counterclockwise to cause closing movement of the breaker rod 11.

In the closed circuit position shown, the breaker rod is latched in position by a latch member 13. The latch 13 is normally biased at 14 toward latching position against a limiting stop 15 to be engaged by a roller 16 carried by the breaker rod. The breaker is normally biased toward open position by the usual breaker springs (not shown) so that when the latch 13 is rotated clockwise about its pivot 13' to release the roller 16, the breaker rod 11 drops rapidly to its open circuit position.

Let it now be assumed that the circuit breaker is to be tripped open in response to a fault condition. The coil 17' of the fault responsive relay indicated at 17 is energized in response to a fault condition to close the contacts at 18 by downward movement of the relay coil plunger 19. The tripping control circuit is thereupon energized from the control source 20 through the relay contacts 18, the latch tripping coil 21 and the contacts 22 of the so-called auxiliary a switch. Upon energization of the trip coil 21, the plunger 21' is projected toward the left to cause clockwise rotation of a lever 23 and corresponding rotation 30 of the latch 13 thereby causing release of the breaker rod 11 and opening of the breaker. The lever 23 is co-pivotedly mounted at 13' with the latch 13 and is disengageably related thereto by an offset portion 23' arranged to engage an extension 13'' of the latch. The breaker is now open and the roller 12 of the lever 8 rests on the upper end of the plunger 7.

The breaker closing operation is performed in the following manner. Assuming now that no fault condition exists, the relay 17 due to its spring bias at 17' closes the closing circuit contacts at 24 so that when the closing button is pressed by the operator to close the contacts at 25 the operating coil 26 of the valve 6 is energized from the control source 20 through the contacts 24 and 25, the pressure indicating auxiliary switch 27 and the contacts of the limit switch 28. When the plunger 28' of the valve solenoid is moved toward the right, it completes 45 a holding circuit at the contacts 28'' so that the closing operation can be completed notwithstanding but momentary closure of the closing button. Simultaneously the slide valve member 50 29, which is reciprocally operable within the valve housing 30 and is normally biased at 31

toward closed position, is moved to uncover the port 32 thereby establishing fluid connection between the source 1 and the cylinder 5. Admission of fluid under pressure to the working face of the piston 4 results in upward movement of the piston and corresponding closing movement of the lever 8 and breaker rod 11.

This closing movement constitutes a strong high speed closing thrust that is effective to close the circuit breaker against the usual spring and contact resistance, at which time the latch 13 is snapped by its spring 14 beneath the breaker rod roller 16 to hold the breaker in the closed position. It will be noted that when the piston 4 is near the upper limit of its travel, it engages the extension 28' of the limit switch 28 to cause opening of the valve solenoid circuit. The valve 6 is thereupon biased to its closed position as indicated. In this position, it will be noted that the valve member 29 defines a passage 28' establishing communication between the cylinder 5 and an exhaust port 30' in the valve housing. The piston 4 is therefore free to settle to its lower or initial position (shown) since the back pressure is now vented to atmosphere. When the valve 29 is in the open position, the exhaust port 30' is covered by the left-hand portion of the valve member.

In the operation so far described, it has been assumed that no fault condition existed that required trip-free operation during the closing stroke. Let it now be assumed that the fault condition which caused the initial tripping and opening of the circuit breaker has not been corrected and that the operative attempts to close the circuit breaker while the fault condition exists. The closing operation is initiated in the manner above described. However, when the breaker nears the end of the closing stroke as the breaker contacts first engage (the a switch now being closed), the fault responsive relay 17 will cause actuation of the tripping solenoid 21 and clockwise movement of the lever 23. This lever, it will be noted, not only causes rotation of the latch 13 to a non-latching position but also engages the extension 33' of a dump valve 33 to cause immediate venting of the cylinder 5 to atmosphere through a comparatively large port 34.

It will therefore be observed that when the dump valve 33 is open the piston 4 is no longer acted upon by a closing force since the operating pressure is practically instantly dissipated even though the valve 6 still be open. In fact, the piston 4 can move to its initial position notwithstanding the continued flow of fluid from the source 1 by reason of the free venting at the dump valve. With this arrangement, the mechanism is completely trip-free during the closing operation and the trip-free operation is moreover instantly responsive to the fault condition for permitting the circuit breaker immediately to return to its open circuit position. The dump valve 33 is spring biased at 35 toward its normally closed position as shown.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. A fluid pressure operating mechanism of the trip-free type for an electric circuit breaker com-

prising a source of fluid pressure, a fluid motor including a piston and cylinder, means disengageably relating said piston to said circuit breaker for closing said breaker, a latch for holding said circuit breaker in closed position independently of said piston so that said piston can return to its initial open position whereby said circuit breaker is normally free to trip open at high speed independently of said piston, a dump valve for venting said cylinder to atmosphere at the working face of said piston whereby said piston can also return to its initial position during a closing operation, and fault responsive means for releasing said latch to cause opening movement of said breaker and for also opening said dump valve for causing trip-free operation.

2. A pneumatic operating mechanism of the trip-free type for an electric circuit breaker comprising a source of compressed air, an operating cylinder and piston arranged to be connected through a control valve to said source, means disengageably relating said piston to said circuit breaker including a linkage, a latch for holding said linkage in closed circuit position, a dump valve for venting at high speed the pressure in said cylinder on the working side of said piston, an actuating member common to said latch and said dump valve, and fault responsive means operatively related to said common actuating member for causing substantially simultaneous release of said latch and opening of said dump valve for trip-free operation.

3. A pneumatic operating mechanism of the trip-free type for an electric circuit breaker comprising a source of compressed gas, a fluid motor including a piston and cylinder, a control valve between said source and cylinder, said valve being arranged to admit gas under pressure from said source to said cylinder and also directly to vent said cylinder to atmosphere, means operatively relating said piston to said circuit breaker for closing said breaker, a latch for holding said circuit breaker in closed position, a dump valve for venting rapidly said cylinder to atmosphere at the working face of said piston whereby said piston can return to its initial position notwithstanding flow of fluid under pressure from said source through said control valve to said cylinder, and means for releasing said latch to cause opening movement of said breaker and for also opening said dump valve for causing trip-free operation.

4. A pneumatic operating mechanism of the trip-free type for an electric circuit breaker comprising a source of compressed gas, an operating cylinder and piston arranged to be connected through a control valve to said source, a lever arranged to be disengageably engaged by said piston for closing said circuit breaker, a latch for holding said lever in closed circuit position whereby said piston can return to its initial position after closing said breaker, a dump valve for venting at high speed the pressure in said cylinder on the working side of said piston notwithstanding continued flow of gas from said source, actuating means common to said latch and said dump valve, and fault responsive means operatively related to said common actuating means for causing trip-free operation by substantially simultaneous release of said latch and opening of said dump valve.

5. A fluid pressure operating mechanism of the trip-free type for an electric circuit breaker comprising a source of fluid pressure, a fluid motor arranged to be connected to said source, means

operatively relating said motor to said circuit breaker for closing said breaker, a latch for holding closed said breaker, a dump valve for instantly venting said fluid motor to permit high speed reversal thereof, said dump valve and latch being mechanically interrelated, and a tripping solenoid operative both to release said latch and to open said dump valve for trip-free operation of said breaker.

6. An operating mechanism for an electric circuit breaker comprising a fluid motor for producing a closing operation of said breaker, a

source of fluid under pressure for operating said motor, a control valve for connecting said source of fluid with said fluid motor for closing said circuit breaker, a latch for holding closed said breaker, and a dump valve directly connected to said fluid motor apart from the connection to said pressure source operable upon the opening movement of said circuit breaker for instantaneously reducing the back pressure against said fluid motor so that high-speed opening operation of said circuit breaker may be obtained.

HAROLD E. STRANG.
